UNITED STATES PATENT OFFICE

116,620

DESIGN FOR A SIGN OR SIMILAR ARTICLE

José Trojan, Chicago, Ill., assignor to Owen Housholder and David C. Cohen, copartners, doing business as Crystal Manufacturing Co., Chicago, Ill.

Application July 20, 1939, Serial No. 86,103

Term of patent 3½ years

To all whom it may concern:

Be it known that I, José Trojan, a citizen of the United States, residing at Chicago, in the county of Cook and State of Illinois, have invented a new, original, and ornamental Design for a Sign or Similar Article, of which the following is a specification, reference being had to the accompanying drawing, forming part thereof.

Figure 1 is a front perspective view of a sign or similar article embodying my new design.

I claim:

The ornamental design for a sign or similar article, substantially as shown.

JOSE TROJAN.
